COMPRESSOR MOUNT PLATE ASSEMBLY

J. Fredrick Vinci, Forest City, Iowa, assignor to
Winnebago Industries, Inc., Forest City, Iowa

Filed Feb. 24, 1975, Ser. No. 552,767

Term of patent 14 years

Int. Cl. D15—02

U.S. Cl. D55—1 H

FIG. 1 is a top perspective view of a compressor mount plate assembly showing my new design;

FIG. 2 is a side elevational view of the right side of FIG. 1, the left side being a mirror image of FIG. 2;

FIG. 3 is an end elevational view of the right end of FIG. 1;

FIG. 4 is an end elevational view of the left side of FIG. 1;

FIG. 5 is a top plan view of FIG. 1; and

FIG. 6 is a bottom plan view of FIG. 1.

I claim:

The ornamental design for a compressor mount plate assembly, substantially as shown and described.
